CARTON LOADING MACHINE

Ruel A. Jones, Covington, Ky., assignor to The
 R. A. Jones & Company, Covington, Ky., a corporation of Kentucky

Application December 20, 1940, Serial No. 371,029

8 Claims. (Cl. 226—2)

This invention relates to packaging machines, and particularly to a type in which articles are placed within cartons.

The cartons usually are made of a paperboard material, each formed to provide a rectangular tube-like container body, with the walls thereof at their opposite ends having flap extensions folded to constitute closures for the open ends of the container. The carton structure for commercial purposes is folded to a flat knock-down position, and in the packaging machine are grouped in their flat condition in a stack within a magazine, from which they are successively withdrawn, erected to put the same in an open condition, and advanced in a successive order in pockets of a conveyor.

The articles to be deposited in the cartons likewise are advanced in pockets of a second conveyor traveling alongside of the carton conveyor and in registry therewith, adapting the articles to be moved endwise into a carton with which they are in registry; whereupon the carton end flaps are folded in their closed position. The travel of the cartons and articles is constant or uninterrupted during the process of packaging and carton closing.

The present invention is directed primarily to the means for pushing or moving the advancing articles into correspondingly advancing cartons. The pockets of the conveyor for the articles to be packaged are open at their opposite longitudinal ends, adapting the article in each pocket to be engaged at one end by a finger and pushed into the open carton during the continued advance of the carton and article conveyors. The fingers respectively depend from an endless chain carrier, superposed above the pockets and disposed to move the fingers transversely and correspondingly in the same direction with the pockets, and centrally therethrough, so that the articles are pushed endwise into the carton without interruption in travel.

A plurality of fingers are effective at the same time, so that the loading is progressively carried on for a plurality of cartons. The fingers and chain carrier, therefore, are supported upon a swinging arm latched in an active position and automatically releasable to swing the loading unit away from and clear of the article carrier conveyor to an inactive position under the slightest retarding pressure or influence imposed on any one of the fingers as resulting from an article encountering any obstruction or interference with its freedom of movement in entering a carton. The releasing throw of the loading unit

controls an electric circuit for the drive of the mechanism to bring the same immediately to a stop or at rest.

It is therefore an object of the invention to load a continuously conveyed or traveling carton with merchandise moving coordinately with the carton and along an open end thereof, and to push the merchandise into the carton by a continuously moving loader unit, the loader unit effective for simultaneously loading a plurality of cartons and adapted to be automatically moved to an inactive position upon the merchandise encountering any resistance in its movement into a carton, and to control the driving power for the carton and merchandise conveying mechanism and loading unit.

Other objects and advantages of the invention will be more fully apparent from a description of the accompanying drawings, in which:

20 Figure 1 is a top plan view of the carton loading portion of the machine, disclosing a section of an adjoining pair of endless conveyors respectively for carrying cartons and articles to be packed or deposited within the cartons, and a conveyor at an elevation above the article conveyor normally at an angle thereto provided with fingers for pushing the articles crosswise from one conveyor into a carton on the second adjoining conveyor.

25 Figure 2 is a side elevation thereof. Figure 3 is a detail top plan view of the rear or pivotally supported end of the loading mechanism, including a diagrammatic illustration of an electric motor controlling circuit.

30 Figure 4 is a section on line 4—4, Figure 1. Figure 5 is a section of a portion of the mechanism shown in Figure 4 of the loading unit in a released or unlatched position.

35 Figure 6 is a section taken on line 6—6, Figure 1.

40 As the present invention is directed solely to the mechanism for loading or pushing the merchandise into the cartons, the drawings and following description thereof are confined to such phase of the machine.

The machine in its complete organization is representative of a type as fully illustrated and described in a prior patent issued to me November 14, 1933, Number 1,935,269, and to which reference may be had for the portions classifiable as separate from the present invention. In the machine of the patent, as herein, fingers dependingly supported from a continuously moving endless chain are employed for pushing the merchandise from within the conveyor translated

open-ended pockets into the cartons. The loading conveyor is positioned to move transversely or at an angle to the merchandise conveyor to advance the fingers thereof in a direction centrally intercepting the pockets and also advancing coordinately therewith.

The machine is preferably designed to operate upon a carton consisting of a rectangular tubular body portion 1 having end closure flaps 2. The cartons are supplied to the machine from a magazine in which they are stacked in a collapsed or flat condition, one upon another. The cartons, as each assumes its lowermost position in the stack, are successively ejected from the magazine and suitably erected and deposited in a spaced order upon an endless conveyor 3. The conveyor in its forward run travels upon a travel supporting plate 4. The cartons in the erected position upon the conveyor are successively engaged by lugs 5 extending laterally from the conveyor, and the cartons slidably bear against a pair of rails 6, 6, extending longitudinally above the forward run of the conveyor to sustain the cartons in erected position upon the conveyor.

The closure flaps extending from the opposite ends of the cartons are held in a fully opened position during the period of loading, and this applies particularly for the end of the carton which initially receives the merchandise in loading. The merchandise for deposit into the cartons is conveyed in pockets 1 of channel form, carried in spaced relation by an endless conveyor 9 traveling alongside of the carton conveyor with the pockets thereof in alignment and registration with the adjoining cartons.

In the drawings, the merchandise for packaging within the cartons is represented as bottles 10, and four thereof in successive order are simultaneously and progressively operated upon for movement into relative cartons, advanced adjoining therewith by the conveyor. The number of bottles operated upon is selected to avoid undue length of the loading unit and a reduction in machine cost.

The loading unit comprises a radial arm 11 at one end pivotally mounted upon a vertically disposed shaft 12 journalled within a bracket 13, vertically mounted upon the frame 14 of the machine. The shaft beneath the pivoted end of the radial arm 11 has a sprocket wheel 15 fixed thereto. The hub of the sprocket wheel in the normal position of the arm bears upon the upper end of the journal 16 of the bracket 13. The sprocket wheel 15 has its teeth engaged with the links of an endless sprocket chain 17, and the chain at the forward end of the arm is engaged about an idler sprocket wheel 18, journalled upon a stud 19, fixed to and laterally projecting from the forward end of the arm. The sprocket chain at uniformly spaced intervals has pins or fingers 20, each secured to a respective link of the chain, and projected laterally therefrom and dependingly from the chain.

The arm in a normal or active position of the loading unit has its forward end over-reaching a section of the merchandise conveyor, with the forward run of the chain traveling at an angle thereto and in a corresponding direction therewith for traversing the fingers centrally intersectingly through the channel of a respective 70 pocket for engaging the merchandise in the pocket and pushing the same therefrom into an adjoining registering carton.

The operation of the loading fingers and their conveying chain, insofar as utilized for pushing 75

the articles from the pockets of one conveyor into the second in alignment therewith on the second conveyor, follows substantially the corresponding parts of the loading mechanism described in the aforesaid prior patent.

In mounting the finger carrying chain upon a swinging radial arm, the loading unit can be swung outwardly away from and clear of the merchandise conveyor, giving freedom of access to the article loading pockets in the event of any jamming or interference in a loading operation. Incidentally, through the pivotal connection of the radial arm upon the drive shaft 12 for the finger carrying chain 17, and the frictional contact with the hub of the driving sprocket 15, there is a tendency to correspondingly rotate the radial arm unless arrested, and this motion is utilized for automatically swinging the arm outwardly to render the loading unit ineffective for loading and to clear the merchandise conveyor.

The arm, therefore, normally is latched in its active position by a spring tensioned plunger 21 slidably supported in a horizontal plane within a tubular head 22 of a bracket 23 fixed upon the machine frame. The plunger within the bore in the head of the bracket is provided with a collar or annular shoulder 24 engaged by an end of a spring 25 about the plunger and housed within said bore. The opposite end of the spring 25 bears against a sleeve nut 26 concentrically about the stem of the plunger and is screwthreaded into the rear end of the bore of the bracket head. Adjustment of the nut 26 provides for a regulation of the tension of the spring 25 for exerting an arresting pressure against the arm, counteracting its rotative tendency administered through its frictional connection with the drive shaft 12 and sprocket wheel 15.

The arm is provided with a radially extended lug 27, the free end of which bears against the head 28 of the plunger 21. However, should any jamming or interference occur in pushing an article from the merchandise conveyor into a carton, applying added resistance to a pusher finger sufficient to overcome the tension of the plunger spring 25, the arm will be moved to unlatch the lug 27 from a latch tooth 29 extending laterally from a latch 30, pivotally mounted on a bracket 31 fixed to the frame of the machine.

The arm or loading unit normally is latched by the latch 30 in a depressed position against the tension of a spring 32 housed in a bore in the journal of the drive shaft 12. The laterally extended tooth 29 of the latch 30 extends through an aperture in the bracket 31 and over the arm lug 27, and a slight rotative or swinging motion of the radial arm 11 will release the lug 27 from the tooth of the latch, whereupon the loading unit will be elevated by the spring 32, moving the fingers above an engaging contact with the articles in the pockets of the merchandise conveyor. This also frees the lug 27 of the radial arm from the plunger 21, leaving the arm free to rotate under the frictional influence with the shaft 12 and driving sprocket wheel 15 until brought to rest by the lug 27 contacting with a stationary stop 33 extending vertically from the plunger supporting bracket 23.

The spring 32 for elevating the loading unit is housed within a bore 34 in the journal portion of the bracket 13, supporting the loading unit, and is coiled about the drive shaft 12 with one end thereof engaged against the inner end of a sleeve 35 concentric about the shaft and slidably within the journal bore 34, so that when the

radial arm is unlatched, the spring 32 will elevate the shaft 12 and its supporting and connecting parts comprising the loading unit. The shaft at its lower end is splined to a gear 36 of the transmission means for rotating the shaft which is in driving connection with the transmission for driving the carton and merchandise conveyors or other power means for synchronously transmitting the several conveyors.

As the drive for the machine generally constitutes an electric motor, the plunger 21 is also utilized for a starting and stopping circuit control for the motor, as illustrated in Figure 3.

The rear end of the plunger 21 has an arm 37 extending laterally therefrom, with its free end carrying a set-screw 38 for contact with a stem 39 of a spring actuated movable electric circuit controlling switch element 40 engageable with a pair of stationary contactors 41, 41. One of the stationary contacts 41 connects with a conductor 42 leading from a source of electric supply, and the second stationary contact 41 is in connection with a stationary contact 43 of a push button self-closing or normally closed stop switch 45 by means of a conductor 44. The movable element 25 of the push button switch normally contacts with a second stationary contact 43. The second stationary contact 43 by means of the conductor 46 connects with stationary contact 47 of a self-opening or normally opened motor starting push 30 button switch 48, and with a stationary contact 49 of a relay switch 50. The second stationary contact of said push button starting and relay switches are connected together by a conductor 51, and in series with the coil of the relay switch, 35 thence to a pole of an electric motor 52, the opposite pole of the motor connecting with the source of electric supply.

The finger carrying sprocket chain 17 longitudinally of the opposite sides of the arm is 40 guided and sustained against sag or flex by a pair of rails 53, 53, fixed upon the underside of the arm. The arm directly sustains the chain, so that any load imposed upon the fingers which constitutes an abnormal pressure thereon, as results from an article encountering any obstruction in 45 its advance into the carton sufficient to depress the trip plunger 21, effects an unlatching of the arm; whereupon, it will be instantly elevated by the spring 32 and moved outwardly to an inactive 50 position and cut off the driving power.

Upon removing the obstruction, the arm can be easily manually swung back to active position and depressed, continuing the operation of the machine. As it is a common practice to include printed matter in an enveloping position over an end of the article, for feeding the same along with the article in the carton, displacement thereof occasionally results, causing a jam between the articles in the cartons, and unless immediately arrested and removed, may result in injuries to the machine.

The power control may be readily modified over the form illustrated herein which is of a conventional character, as it is obvious that various forms for electric circuit controlling switch devices may be employed operated by the arm from some other point than that herein selected.

The rotation of the drive shaft 12 has a tendency to swing the arm bodily on its axis because of a degree of friction inherent in the unit plus the loading effect of the articles being translated in the conveyor pockets. These forces are counteracted by the spring loaded latch plunger 21, regulated by the adjustable sleeve nut 26 for 75

the pressure necessary to poised the arm in position for normal operation, and to trip immediately when any undue resistance or overload occurs.

5 The plunger is regulated for a pressure commensurate with the weight and other characteristics of the articles. In handling light fragile articles, for example tooth-paste tubes, wherein any undue pressure would dent or mar the tube and render it unfit as merchandise, the plunger is spring loaded just slightly in excess of that necessary to overcome the normal release thrust of the arm to permit the arm to trip readily should any obstruction occur in the transfer of the tubes, with little or no damage to the tubes. Upon release, the arm rises vertically and swings radially to a position clear of the conveyor pockets, and the mechanism stopped for correction by an attendant.

Having described my invention, I claim:

1. In a carton loading machine, a pair of endless conveyors, one for continuously advancing cartons in a consecutive order and the second having pockets for correspondingly continuously advancing merchandise for packing into the cartons, the conveyors moving the carton and the pockets with their contents in adjoining endwise registration, whereupon upon relative movement of the merchandise and cartons, the merchandise is inserted respectively into the carton, an endless carton loading conveyor and a movable support therefor sustaining the same above said merchandise conveyor with the forward run of the conveyor moving obliquely across and directionally with the merchandise conveyor, and carrying fingers, each for traversing a merchandise conveying pocket for moving the merchandise therein into a registering carton, said support movable by the transmitting power of the carton loading conveyor for displacing the conveyor and dislodging the fingers from said conveyor pocket traverse, and latching means for holding said support in an active position automatically releasable by the pressure exerted by a finger encountering resistance in loading the merchandise from the pockets into the cartons.

2. In a carton loading machine, a pair of endless conveyors, one for continuously advancing cartons in a consecutive order and the second having pockets for correspondingly continuously advancing merchandise for packaging into the cartons, the conveyors moving the cartons and the pockets with their contents in adjoining endwise registration, whereupon upon relative movement of the merchandise and cartons, the merchandise is inserted respectively into the cartons, an endless carton loading conveyor movably sustained above said merchandise conveyor with the forward run of the loading conveyor moving obliquely across and directionally with the merchandise conveyor, and carrying fingers, each for traversing a merchandise conveying pocket for moving the merchandise therein into a registering carton, said loading conveyor movable for displacing the loading conveyor and dislodging the fingers from said conveyor pocket traverse, and latching means for holding said loading conveyor in an active position automatically releasable by pressure exerted by a finger encountering resistance in loading the merchandise from a pocket into a carton.

3. In a carton loading machine, a pair of endless conveyors, one for continuously advancing cartons in a consecutive order and the second having pockets for correspondingly continuously

advancing merchandise for packaging into the cartons, the conveyors moving the cartons and the pockets with their contents in adjoining endwise registration, whereupon upon relative movement of the merchandise and cartons, the merchandise is inserted respectively into the cartons, an endless carton loading conveyor movably sustained above said merchandise conveyor with the forward run of the loading conveyor moving obliquely across and directionally with the merchandise conveyor, and carrying fingers, each for traversing a merchandise conveying pocket for moving the merchandise therein into a registering carton, said loading conveyor movable for displacing the loading conveyor and dislodging the fingers from said conveyor pocket traverse, latching means for holding said loading conveyor in an active position automatically releasable by pressure exerted by a finger encountering resistance in loading the merchandise from a pocket into a carton, and means actuated by the displacing movement of said loading conveyor for controlling the power transmission of all of said conveyors.

4. In a carton loading machine, a pair of endless conveyors, one for continuously advancing cartons in a consecutive order and the second having pockets for correspondingly continuously advancing merchandise for packaging into the cartons, the conveyors moving the cartons and the pockets with their contents in adjoining endwise registration, whereupon upon relative movement of the merchandise and cartons, the merchandise is inserted respectively into the cartons, an endless carton loading conveyor movably supported above one of said conveyors with the forward run of the loading conveyor moving obliquely across and directionally therewith, and carrying fingers, each for imparting relative movement to said merchandise and cartons for inserting the merchandise into a registering carton, said loading conveyor movable to a non-loading position, and latching means for holding said loading conveyor in an active position automatically releasable by pressure exerted by a finger encountering resistance in loading the merchandise into a carton.

5. In a carton loading machine, a pair of endless conveyors, one for continuously advancing cartons in a consecutive order and the second having pockets for correspondingly continuously advancing merchandise for packaging into the cartons, the conveyors moving the cartons and the pockets with their contents in adjoining endwise registration, whereupon upon relative movement of the merchandise and cartons, the merchandise is inserted respectively into the cartons, an endless carton loading conveyor movably supported above one of said conveyors with the forward run of the loading conveyor moving obliquely across and directionally therewith, and carrying fingers, each for imparting relative movement to said merchandise and cartons for inserting the merchandise into a registering carton, said loading conveyor movable to a non-loading position, latching means for holding said loading conveyor in an active position automatically releasable by pressure exerted by a finger encountering resistance in loading the merchandise into a carton, and means actuated by the movement of the loading conveyor to a non-loading position for power stopping transmission control for said conveyor.

6. In a carton loading machine, a pair of endless conveyors, one for continuously advancing

cartons in a consecutive order and the second for correspondingly continuously advancing merchandise for packaging into the cartons, the conveyors moving the cartons and merchandise in adjoining endwise registration, whereupon upon relative movement thereof the merchandise is inserted respectively into the carton, an endless carton loading conveyor carrying fingers, each for moving the merchandise into a registering carton, a radial arm pivotally mounted for supporting said loading conveyor in a loading position above said merchandise conveyor, with the forward run of the conveyor moving the fingers in a line obliquely across and directionally with the merchandise conveyor or in a non-loading position away from the merchandise conveyor, and latching means for holding said radial arm in a loading position automatically releasable by the pressure exerted through a finger encountering resistance in loading the merchandise into a carton, and causing movement of the arm to a non-loading position.

7. In a carton loading machine, a pair of endless conveyors, one for advancing cartons in a consecutive order and the second for correspondingly advancing merchandise for packaging into the cartons, the conveyors moving the cartons and merchandise in adjoining endwise registration, whereupon upon relative movement thereof the merchandise is inserted respectively into the carton, an endless carton loading conveyor carrying fingers, each for loading the merchandise into a registering carton, a radial arm pivotally mounted for supporting said loading conveyor in a loading position above said merchandise conveyor, with the forward run of the loading conveyor moving the fingers in a line obliquely across and directionally with the merchandise conveyor and perpendicularly movable for elevating the fingers to a non-loading position and away from the merchandise conveyor, and latching means for holding said radial arm in a loading position automatically releasable by the pressure initiated by a finger encountering resistance in loading the merchandise into a carton, and free the arm for movement of the conveyor finger to a non-loading position.

8. In a carton loading machine, a pair of endless conveyors, one for continuously advancing cartons in a consecutive order and the second for correspondingly continuously advancing merchandise for packaging into the cartons, the conveyors moving the cartons and merchandise in adjoining endwise registration, whereupon upon relative movement thereof the merchandise is inserted respectively into the cartons, an endless carton loading conveyor carrying fingers, each for moving the merchandise into a registering carton, a radial arm pivotally mounted for supporting said loading conveyor in a loading position above said merchandise conveyor, with the forward run of the conveyor moving the fingers in a line obliquely across and directionally with the merchandise conveyor and to swing the arm to position the conveyor in a non-loading position away from the merchandise conveyor, said arm yieldingly movable perpendicularly to elevate the finger to an inactive position, and latching means for holding said radial arm in a loading position automatically releasable by pressure imposed through a finger encountering resistance in loading the merchandise into a carton for movement of the arm to a non-loading position.
